Patented June 5, 1923.

UNITED STATES PATENT OFFICE.

JAMES A. TAYLOR, OF WACO, KENTUCKY.

COLLAR BUTTON AND TIE HOLDER.

Application filed November 2, 1922. Serial No. 598,580.

To all whom it may concern:

Be it known that I, JAMES A. TAYLOR, a citizen of the United States, residing at Waco, in the county of Madison, State of Kentucky, have invented a new and useful Collar Button and Tie Holder; and I do hereby declare the following to be a full, clear, and exact description of the invention, such as will enable others skilled in the art 10 to which it appertains to make and use the same.

The invention relates to collar buttons and has for its object to provide in combination with the pivoted head of a collar button, an 15 elongated pin, which pin, when the collar button is in place, prevents displacement of the tie in relation to the collar, particularly downward displacement.

A further object is to form the pin from 20 a single length of wire, said pin being disposed outside of the pivoted collar button head and the body formed into a loop, which loop engages expansibly within the collar button head and holds the pin against displacement. Also to provide means whereby 25 when the pivoted head is moved from a parallel relation with the base of the button the free end of the pin will be forced inwardly where it will engage the pivoted head, there- 30 by allowing the pivoted head to be easily forced through a button hole.

With the above and other objects in view the invention resides in the combination and arrangement of parts as hereinafter set 35 forth, shown in the drawing, described and claimed, it being understood that changes in the precise embodiment of the invention may be made within the scope of what is claimed without departing from the spirit 40 of the invention.

In the drawing:—

Figure 1 is a perspective view of the collar button, showing the pin applied thereto.

Figure 2 is a side elevation of the collar button showing the pivoted head in longitudinal vertical cross section.

Figure 3 is a perspective view showing the button applied to a collar.

Referring to the drawing, the numeral 1 50 designates the base of the collar button, 2 the post carried thereby and 3 the pivoted head which is pivoted at 4 to the post 2, in the usual manner. The elongated head 3 is 55 provided on its underside with an inwardly extending marginal flange 5, and disposed

within the chamber 6 of the head 3 and engaging the inner side of the flange 5 is an expandible looped member 7, which looped member terminates in an upwardly extending portion 8, which passes through an aperture 9 adjacent one end of the pivoted head 3 and substantially in alignment with the longitudinal center line of the pivoted head 3 and terminates in a rearwardly extending curved pin 10, which normally engages the outer face of the head 3, when said head is at a right angle to the base in such a manner that it will not interfere with the passing of the pivoted head through shirt band 70 and collar apertures. After the collar button has been placed in the position shown in Figure 3, it will be seen that the pin 10 will pierce the neck tie 11 and prevent downward movement thereof, thereby preventing 75 the neck tie from working downwardly. Where a standing collar is used, the collar is placed in position so that the pin will point downwardly and consequently when in piercing engagement with the tie will 80 prevent upward movement of the tie. The upper end of the post 2 is provided with a lug 12, which lug extends through an aperture 13 in the pivoted head 3 when the pivoted head is moved to a position in parallel relation to the base 1, and engages the free end of the pin 10 and forces the same 85 upwardly to a position where it will pierce the neck tie 11. When the head is being forced through the collar it is in substantial 90 alignment with the post 2 and consequently lug 12 is out of engagement with the free end of the pin, thereby allowing the pin to come into close engagement with the upper 95 face of the head where it will not interfere with the passage of a button through a button hole or injure the hands of the user.

From the above it will be seen that a combined collar button and tie holder is provided, which is simple in construction, may be used in connection with a turned down or standing collar, and one wherein the pin is secured to the pivoted head 3 in such a manner that it is positively held and the use 100 of soldering is eliminated.

The invention having been set forth what is claimed as new and useful is:—

1. A collar button comprising a base, a post carried by said base, a head pivotally mounted on said post, the upper end of the post extending through an aperture in the head, a pin carried by the head and having 110

one of its ends anchored to the head adjacent one side thereof, the free end of the pin extending across the aperture in the head, said upper end of the post forming means whereby upon a movement of the head to a position in parallel relation to the base the free end of the pin will be forced outwardly.

2. The combination with the pivoted head of a collar button, said pivoted head being provided with an inwardly extending flange on its underside, of a pin carried by said pivoted head and engaging the outer face thereof, said pin having one of its ends extending through an aperture adjacent one end of the head, an integral expansible loop

carried by the pin and disposed within the pivoted head and in engagement with the inner side of the inwardly extending flange, and means whereby during the pivotal movement of the head the free end of the pin will be forced out of engagement with the outer face of the head.

In testimony whereof I have signed my name to this specification in the presence of two subscribing witnesses.

JAMES A. TAYLOR.
